(57) **CLAIM**

The ornamental design for a spray gun, as shown and described.

DESCRIPTION

FIG. 1 is a perspective view of a spray gun according to the present invention.

FIG. 2 is a front view of the spray gun of FIG. 1.

FIG. 3 is a back view of the spray gun of FIG. 1.

FIG. 4 is a right side view of the spray gun of FIG. 1.

FIG. 5 is a left side view of the spray gun of FIG. 1.

FIG. 6 is a top view of the spray gun of FIG. 1; and,

FIG. 7 is a bottom view of the spray gun of FIG. 1.

The features shown in broken line are for illustrative purposes only and form no part of the claimed invention.
